PROPELLING PENCIL

Nándor Nagy, Budapest, Hungary, assignor to
firm: Koh-i-noor Bleistiftfabrik L. & C. Hardt-
muth, Bohm-Budweis, Czechoslovakia

Application August 16, 1933, Serial No. 685,443
In Hungary August 22, 1932

3 Claims. (Cl. 120—17)

My invention relates to a propelling pencil which is simple in design, inexpensive to make and very easy to operate. The propelling pencil according to my invention further offers the advantage that leads of any desired length, up to almost the entire length of the instrument, may be employed and used up to a residue of negligible size, the lead being always guided safely and secured against rotation. Another advantage 5 of the invention resides in the possibility of concealing the lead in the outer shell if desired and propelling it for use by a simple operation, a protective cap therefore being unnecessary.

In the propelling pencil according to my invention, the feeding of the lead is not effected, as more usual, by rotation but by depression of a cap provided on the rear end of the instrument. According to the invention, this movable cap is connected to or integral with the extremity of a 10 feeding tube slidable in the outer shell or barrel of the pencil and urged rearward by a spring. The feeding tube is cylindrical and provided on its inner wall along a generating line of the cylinder with ratchet teeth. These teeth cooperate with 15 a resilient projection or tongue of a cylindrical feeding rod slidable in a guide tube mounted in the pencil. This guide tube projects into the feeding tube and is slotted along a generating line in order to allow the tongue of the feeding rod 20 to project beyond this tube and to engage the inner wall of the feeding tube. If the feeding tube is shifted forward by pressing a finger upon its protruding rear extremity, the resilient tongue 25 of the feeding bar or rod is engaged by the teeth and the feeding rod is moved forward and the lead propelled.

If the pressure exerted upon the end of the feeding tube is relieved, said tube is moved back to its initial position by a spring; the feeding 30 rod will not follow this rearward movement because of the friction in the guide tube and its tongue will engage another ratchet tooth. The ratchet teeth on the inner surface of the feeding tube are preferably of arcuate cross-section in 35 order to make it possible to bring the tongue of the feeding rod in and out of engagement with said teeth by rotating said rod relative to the feeding tube. The pencil is further improved by providing a longitudinal fin or rib in the guide 40 tube engaging a recess of the feeding rod and locking the latter against rotation. In this case, the lead is also provided with a longitudinal recess and also locked against rotation.

The invention will now be fully described with 45 reference to the accompanying drawing, in

which: Fig. 1 shows the whole structure in an axial section, the front portion being designated by E and the rear portion by H. Fig. 2 is an end view of the rear portion, Fig. 3 a cross section of the lead, Fig. 4 an axial section of the guide tube, Fig. 5 a cross section of the same, Fig. 6 a side view and Fig. 7 an end view of the tapered extremity of the guide tube in an enlarged scale, Fig. 8 an axial section of the feeding tube, Fig. 9 a cross section of the same along line 9—9 of 10 Fig. 8, Fig. 10 a like section along the line 10—10 of Fig. 8 (viewed from the rear end). Fig. 11 is an axial section of the outer shell or barrel Fig. 12 is a section on the line 12—12 of Fig. 11. Fig. 13 shows the spring. Fig. 14 the end cap 15 in axial section. Fig. 15 the same cap in cross section on the line 15—15 of Fig. 14. Fig. 16 is a side view of the feeding bar. Fig. 17 a section on the line 17—17 of Fig. 16, and Fig. 18 is a sectional view on the line 18—18 of Fig. 16. 20

The lead is cylindrical with circular cross section and provided along its whole length with a recess or groove 8 engaging a rib or fin 9 protruding from the inner wall of the guide tube 2. Thus, the lead is movable back and forth but 25 cannot be rotated.

The guide tube 2 bears a flange 10 abutting upon a shoulder in the bore of the outer shell or barrel 4. Flange 10 may be dispensed with if the guide tube 2 is secured by means of adhesive or 30 in any other suitable manner in the interior of the tapered end of the barrel. The front end 2a of the guide tube 2 has greater outer diameter and is slotted at 12 (see Fig. 6). The other portion of tube 2 extending rearward from flange 10 35 has somewhat smaller outer diameter and is provided with a longitudinal slot 14 opposite to the rib 9. This slot allows the tongue 15 of the feeding rod 7 to pass. The front end of tube 2 is made resilient by the slots 12 and prevents 40 any lateral movement of the lead 1 inserted into tube 2.

The interior wall surface of tube 3 is provided along its whole length, but only over a part of 45 its circumference, with notches cut into the wall of the tube producing teeth 16 not protruding into its clearance. (See Fig. 9.) The teeth 16 of the rack thus formed cooperate with the tongue 15 of the feeding bar 7. The feeding tube 3 is provided near its rear end with a flange 17 serving 50 as an abutment for spring 5 and also keeping the tube 3 from leaving the barrel 4. Flange 17 extends over part of the outer circumference of tube 3 only (see Fig. 10) in order to limit the 55 rotation of tube 3; the ends 18 of said flange

engaging a boss provided on the interior wall of the closing cap 6 (as shown by Figs. 14 and 15a). Thus it is possible to bring the tongue 15 by a short rotation of the feeding tube 3 into and out of engagement with the teeth 16. In order to facilitate rotation of the tube 3, the rear end 20 of the same, protruding from the barrel 4 and passing through the rear end of cap 6 is milled at 20a.

10 Spring 5 bears with one of its ends against the end 24 of the barrel 4. Its other end presses flange 17 of the feeding tube 3 continuously against the inner ends 21 of cap 6. This cap is secured on the rear end of the barrel 4 made 15 of wood or any other suitable material and preferably of octagonal shape. The barrel is bored centrally and split in two like parts which after insertion of the guide tube 2 are united by means of adhesive or in any other suitable manner.

20 15 The feeding bar 7 is made of spring steel and has circular cross section in its front portion while its rear portion is prismatic and forms the tongue or projection 15 engaging with its end the teeth 16. The middle portion of bar 7 is slightly 25 reduced to ensure light and smooth spring action against the ratchet teeth 16. The cylindrical part of the feeding rod is provided with a groove 22a corresponding to the groove 8 of lead 1.

30 The propelling pencil according to the invention is operated as follows: First the lead 1 is inserted into the guide tube 2, care being taken that rib 9 of the latter engages the recess 8 of the lead. Then the feeding bar 7 is inserted, with its cylindrical portion directed against the tip 35 of the pencil, into the guide tube 2 in such a manner that the rib 9 of the latter engages the recess 22a. The tongue 15 extends through slot 14 of the guide tube and engages the inner surface of the feeding tube. Now the operator grasps the milled 40 end 20 of said tube and turns it, bringing the tongue 15 of the feeding bar 7 into engagement with the teeth of the feeding tube 3. After this is done, the rear end 20 of the feeding tube 3, protruding from the barrel 4, is pressed into the 45 latter with a finger, in order to move the front edge 25 of tube 3 into the space left between said end and the flange 10 of tube 2. (See Fig. 1). By this movement, the feeding rod 7 engaging with its tongue the ratchet teeth 16 and also the lead 50 1 are fed forward. If the finger pressure is relieved, spring 5 moves the feeding tube backwards. During this movement the tongue 15 slides over the ratchet teeth 16 and engages another tooth of the rack. Any backward movement of the lead 1 during writing is thus made impossible. If the operation just described is repeated, the lead is successively propelled and may be used 55 up until a very small residue is left, the feeding tube being provided substantially along its whole 60 length with ratchet teeth.

If it is desired to push the lead 1 entirely back into the guide tube 2 or if a new lead is to be inserted, it is only necessary to turn the milled end of tube 3, thus bringing the resilient tongue 65 15 of the feeding bar 7 out of engagement with the rack teeth 16. If this is done, the lead may be pressed into the tube 2 with the finger or otherwise. The tongue 15 slides in this case along

the inner wall of tube 3 without offering any appreciable resistance. If the feeding tube 3 is turned again to its initial position, the tongue 15 reengages the teeth 16 and the lead may be brought again into the writing position, as previously described. The two positions of tube 3 are defined by the engagement of the boss 19 with one of the ends 18 of flange 17.

5 The embodiment of the invention as shown offers the advantage that the feeding bar is positively guided and any possible clogging of the tongue 15 is avoided.

What I claim is:

1. In a propelling pencil a guide tube provided with a longitudinal rib projecting from its inner wall receiving the lead having a longitudinal groove, said guide tube being secured to the front portion of the barrel, a feeding tube arranged within the barrel and surrounding said guide tube, said feeding tube being movable from outside toward the tip of the pencil against the action of a spring and a feeding bar having a longitudinal groove engaging said rib of the guide tube, said feeding bar being slidably in said guide tube extending with a resilient tongue through a longitudinal slot of said guide tube and engaging with said tongue the inner wall of the feeding tube.

2. In a propelling pencil a guide tube provided with a longitudinal rib projecting from its inner wall receiving the lead having a longitudinal groove, said guide tube being secured to the front portion of the barrel, a feeding tube arranged within the barrel and surrounding said guide tube, said feeding tube being movable from outside toward the tip of the pencil against the action of a spring and a feeding bar having a longitudinal groove engaging said rib of the guide tube, said feeding bar being slidably in said guide tube, extending with a resilient tongue through a longitudinal slot of said guide tube and engaging with said tongue the inner wall of the feeding tube, said inner wall being provided along its whole length but only over a part of its circumference with ratchet teeth of arcuate cross- 45

3. In a propelling pencil a guide tube provided with a longitudinal rib projecting from its inner wall receiving the lead having a longitudinal groove, said guide tube being secured to the front portion of the barrel, a feeding tube arranged within the barrel and surrounding said guide tube, said feeding tube being movable from outside toward the tip of the pencil against the action of a spring and a feeding bar having a longitudinal groove engaging said rib of the guide tube, said feeding bar being slidably in said guide tube extending with a resilient tongue through a longitudinal slot of said guide tube and engaging with said tongue the inner wall of the feeding tube, said inner wall being provided along its whole length but only over a part of its circumference with ratchet teeth of arcuate cross-section, the feeding tube being movable axially and rotatable to bring the resilient tongue in and out of engagement with the ratchet teeth.

NÁNDOR NAGY.
